UNITED STATES PATENT OFFICE.

ARTHUR E. BYRD, OF MILWAUKEE, WISCONSIN, ASSIGNOR TO PHOENIX HOSIERY COMPANY, OF MILWAUKEE, WISCONSIN, A CORPORATION OF WISCONSIN.

YARN GUIDE.

Application filed July 24, 1925. Serial No. 45,747.

To all whom it may concern:

Be it known that I, ARTHUR E. BYRD, a citizen of the United States, residing at Milwaukee, in the county of Milwaukee and 5 State of Wisconsin, have invented a certain new and useful Improvement in Yarn Guides, of which the following is a full, clear, concise, and exact description, reference being had to the accompanying drawings, forming a part of this specification.

My invention relates to yarn guides particularly adaptable in circular knitting machines for guiding the yarn from the supply cones to the needles of the needle cylinders.

15 These yarn guide structures comprise a guide bracket and a guide plate and the object of the invention is to make flexible and yieldable the heretofore rigid guide plates so as to permit them to be set close to the cylinder needles so that as said needles travel past the plates they will always be in contact therewith and will cooperate with the plates to fully receive the yarn to eliminate the dropping of stitches to prevent tearing of 20 the yarn, and to prevent strain on and breakage of needles heretofore caused by the catching of the needle hooks in knots, bunches, spread sections, or other irregularities in the 25 yarn. By means of my invention, needle 30 breakage is reduced to a minimum, and I also eliminate the delay heretofore required in replacing the broken needles and untangling the torn fabric, whereby the fabric production is materially increased and also a more 35 uniform quality assured.

On the drawings, illustrating my invention,

Figure 1 is a front elevational view of a section of the needle supporting and carrying parts, and one of the improved yarn 40 guide structures;

Figure 2 is a sectional view of the guide structure on plane 2—2, Figure 1, and

Figure 3 is a side elevational view with the guide plate partly in section and showing 45 its cooperation with the cylinder needles.

Fig. 4 is a fragmentary view of the reverse side of the guide shown in Fig. 1.

On the drawings, 10 represents the needle cylinder, 11 the needle dial and 12 the dial cap. The cylinder 10 has the guideways 13 for the vertical needles 14 while the dial has the guideways 15 for the horizontal needles 16. Below the cylinder 10 is the cam cylinder 17 having the camway 18 for 50 engaging with and controlling the vertical

reciprocation of the cylinder needles in a manner well known in the art. The machine may be of the type in which the needle cylinder and dial revolve, or are stationary. In the arrangement shown, the cylinder and dial are supposed to rotate while the dial cap and cam cylinder are stationary.

Mounted on top of the dial cap 12 and equally spaced thereon are a number of guide structures G of which one is shown, 65 the guide structures serving to guide the yarn Y from the supply cones (not shown), which are also supported from the dial cap 12. The guide frame or bracket for each 70 guide structure is L-shaped, its base 19 being secured to the dial cap by a screw 20. The upright member 21 of the bracket extends first vertically and then deflects laterally radially and outwardly and terminates in a shelf 22 in which are seated one 75 or more guide bushings 23 for the yarn. The base of the bracket overhangs the edge of the dial cap and in the outer face of the upright part 21 is provided the vertical 80 guide channel 24 for receiving and guiding the yarn guide plate 25. At its lower end the guide plate is expanded laterally to form the needle guide point or toe 26 and the yarn guide heel 27, the needle cylinder and dial 85 rotating in the direction indicated by the arrow of Figure 1. The yarn coming through the guide bushing 23 extends through the guide opening or eye 28 from the front to the rear thereof and is received by and carried with the needles as the cylinder and dial rotate, all in the well known 90 manner.

As the cylinder and dial rotate, the cylinder needles travel through the camways 18 below the respective yarn guide structures, so that the needles are raised with their hooked ends above the guide opening 28 as they travel past and behind the foot of the yarn guide plates 25, the needles, consecutively, as they travel downwardly, hooking around and receiving the 95 yarn and carrying it to the corresponding dial needles.

The yarn fed to the needles is not always 100 uniform. It may have knots, bunches, loose ends, spread sections, and other irregularities, and it may waver or loop. Unless the hooked ends of the cylinder needles are 105 kept in intimate contact with the guide plates of the guide structures, the hooked ends may not fully and accurately 110 re-

ceive the yarn or the irregular or distorted sections thereof and the hooks may catch in the knots or take on only a part of the yarn strands. This, of course, will result in interference with the proper operation of the needles and they may become bent or displaced and a serious breakage and displacement of needles may occur and tearing of the fabric, a condition well known to knitters. The important object of my invention is, therefore, to provide arrangements which will keep the guide plates and needles in intimate association and I accomplish this by making the guide plates yielding and causing them to be yieldably held against the needles. As shown, each guide plate, at its upper end, is supported by a bolt 29 which passes through a plate 30 on the rear side of the vertical part 21 of the guide structure and is engaged by a nut 31. A wing nut 32 extends through a slot 33 in the plate 30 and threads into the bracket part 21. The bolt 29 extends through the slot 34 in the part 21 so that the guide plates and the back plates 30 may be shifted or adjusted vertically. The bolt 29 threads into the back plate 30 and is locked by nut 31. Between the head of the bolt and the guide plate is inserted a leaf spring 35, so that the connection between the bolt and the plate is flexible and the plate may yield in radial direction relative to the needle cylinder. The ends of the spring are deflected inwardly to rest against the plate and one end of the spring is engaged in the notch or pocket 36 to lock the spring against rotation. The guide plates of the guide structures are thus radially yieldable and are vertically adjustable. By this spring action the plates are held yieldingly against the hooked ends of the cylinder needles 14 as these needles travel past the guide plate feet. This is shown in Figures 3 and 4. With this arrangement, as the needles travel and are vertically raised toward their upward position ready to descend and hook the yarn, their hooks will be in close engagement with the guide plates and complete entry of the yarn, and any irregularities therein into the hooks, will follow. Should the slugs, knots or other uneven sections be of considerable size, the yielding guide plates will permit them to pass through without obstruction and will thus avoid breaking of the yarn and holes in the fabric.

By means of my invention the breakage of needles has been reduced as much as seventy-five (75%) per cent, as compared to the usual breakage in machines with the rigid guide plates. This, of course, results in great saving of time and material and also assures more uniform fabric.

Having described my invention, I claim as follows:

1. In a circular knitting machine, the combination of the needle cylinder and vertically reciprocating needles thereon, a bracket supported above said cylinder and having a yarn guide arm, a supporting plate vertically adjustable on the rear side of said arm, a yarn guide plate reciprocable vertically along the front of said arm and secured to said supporting plate to be adjustable therewith, the lower end of said guide plate being in front of the reciprocating needles and having a yarn guide opening therethrough through which yarn may pass to be received by the needles, and a spring anchored at its upper end to said guide plate and pressing at its lower end against said guide plate to hold it yieldably toward said needles whereby the engagement between said guide plates and needles will be yielding. 75

2. In a knitting machine, the combination of a cylinder, needles vertically reciprocable at the periphery of said cylinder, a bracket mounted above said cylinder, a supporting plate engaging against the back of said bracket, a yarn guide plate at the front of said bracket, said bracket having a vertical slot, a connecting member extending through said slot for connecting said guide plate with said supporting plate, means for securing said supporting plate in vertical adjusted position, and a flat spring anchored intermediate its ends by said securing means and pressing at its ends against said guide plate whereby said plate 100 may yield to abnormal pressure against it by said needles. 85

3. In a circular knitting machine, the combination of a needle cylinder and needles vertically reciprocable around the periphery thereof, a bracket supported above said cylinder and having a yarn guiding arm, a supporting plate engaging against the back of said bracket, a yarn guiding plate engaging against the front of said bracket, 105 said bracket having a vertical slot, a bolt extending through said slot for securing said guiding plate to said supporting plate, said supporting plate being vertically shiftable whereby to vertically adjust said guiding plate relative to said needles, means for securing said supporting plate in adjusted position, said guide plate having a yarn opening through which the yarn passes from said guiding arm to be received by 120 the vertically reciprocating needles, and a spring engaged under the end of said bolt and pressing against said guiding plate whereby said plate may yield to abnormal pressure against it by said needles when 125 receiving yarn therefrom. 110

4. In a circular knitting machine, the combination of a needle cylinder and needles reciprocable vertically along the periphery thereof, a yarn guide arm overhanging said 130

cylinder and having a yarn guiding passageway at its upper end, a supporting plate engaging the rear side of said arm; a yarn guiding plate engaging the front side of said arm and having a yarn guiding opening at its lower end through which the yarn may pass to be received by the needles, an interconnection between said plates, said arm having a vertical slot through which said interconnection passes whereby said

plates may be vertically adjusted, means for locking said plates in adjusted position, and a spring held by said interconnecting means and engaging with said guiding plate to permit yield of said plate under abnormal ¹⁵ pressure thereagainst by said needles when cooperating therewith to receive the yarn.

In witness whereof, I hereunto subscribe my name this 20th day of July, 1925.

ARTHUR E. BYRD.
